UNITED STATES PATENT OFFICE.

FREDERICK W. GORDON, OF PHILADELPHIA, PENNSYLVANIA.

VALVE.

SPECIFICATION forming part of Letters Patent No. 624,790, dated May 9, 1899.

Application filed June 21, 1897. Renewed February 23, 1899. Serial No. 706,552. (No model.)

To all whom it may concern:

Be it known that I, FREDERICK W. GORDON, of Philadelphia, Philadelphia county, Pennsylvania, have invented certain new and useful Improvements in Valves, of which the following is a specification.

This invention relates to valves for use in connection with engines, pumps, compressors, &c., and the improvements will be readily understood from the following description, taken in connection with the accompanying drawings, which description and drawings are directed to a merely exemplifying embodiment of my improved valves in a steam-engine where the valves are used for the admission and exhaust of steam.

In the drawings, Figure 1 is a side elevation of one end of a steam-engine cylinder equipped with my improved valves; Fig. 2, a vertical longitudinal section of the same in the plane of line *a* of Figs. 5, 6, and 7; Fig. 3, a similar section in the same plane of one of the valve-cylinders; Fig. 4, a side elevation of one of the valve-pistons; Fig. 5, a vertical transverse section of one of the valve-cylinders with its valve-piston, taken in the plane of line *b* of Figs. 2 and 4; Fig. 6, a plan of the general structure shown in Fig. 1, and Fig. 7 an end elevation of the same.

30 In the drawings, 1 indicates an end of the cylinder of a steam-engine; 2, the cylinder-head thereof; 3, a chamber formed in the cylinder-head and forming a steam-chest, the drawings showing this chamber as comprehending one half of the area of the cylinder-head; 4, a similar chamber comprehending the other half of the area of the cylinder-head and forming the exhaust-chamber; 5, connections to these chambers for the reception of suitable piping; 6, a valve-cylinder extending entirely across chamber 3, its axis being parallel with the axis of engine-cylinder 1, the inner end of cylinder 6 being open to the engine-cylinder, while its outer end is closed by a bonnet; 7, a circumferential series of ports in cylinder 6, placing the interior of cylinder 6 in communication with chamber 3, the inner edge of port 7 being as close as practicable to the inner face of cylinder-head 2; 8, a valve-piston fitting within cylinder 6 and adapted for reciprocation therein, so as to cover and uncover ports 7,

Fig. 2 showing this valve-piston as being line and line with the ports—that is to say, just covering the ports—the drawings showing valve-piston 8 as being provided with a packing-ring, which ring is of preferable employment; 9, a second valve-cylinder similar to cylinder 6 and disposed below cylinder 6; 10, a circumferential series of ports in cylinder 9; 11, 60 a hollow valve-piston working within cylinder 9, and 12 a circumferential series of ports through the peripheral wall of piston 11 and always in communication with ports 10 in cylinder 9, Fig. 2 showing cylinder 9 as being provided with a packing-ring engaging piston 11, the inner ends of ports 12 appearing in the drawings as being line and line with the forward end of cylinder 9—that is to say, if piston 11 moves to the right ports 12 will 70 begin to open. Two cylinders 6 and 9, with their accompaniments, are thus provided in chamber 3, these two cylinders, with their pistons, constituting a coöperating pair, their pistons being coupled together. They are 75 the steam-valves for the end of the cylinder under consideration. The other chamber 4 in the cylinder-head contains a similar pair of coöperating valves constituting the exhaust-valves, and the description heretofore 80 given of the steam-valves will apply to the exhaust-valves.

Proceeding with the drawings, 13 indicates a valve-stem projecting from each valve-piston outwardly through suitable stuffing-boxes 85 in the bonnets of the valve-cylinders; 14, a cross-head on the outer end of each valve-stem; 15, a pair of rock-shafts mounted in suitable bearings on the cylinder-head, there being one of these rock-shafts for the pair of 90 steam-valves and one for the pair of exhaust-valves, the rock-shafts being in a horizontal plane midway between the axes of the upper and lower valves of the pairs, the inner ends of the rock-shafts being somewhat outside the 95 vertical planes of the axes of their appropriate valves; 16, a double-ended arm fast on the inner end of each rock-shaft just to the outside of cross-heads 14; 17, blocks engaging vertical slots in cross-heads 14 and 100 mounted on inwardly-projecting pins on arms 16, so that the rocking of a given arm 16 will move one valve-piston of the appropriate pair in one direction, while it moves the other

valve-piston of that pair in an opposite direction; 18, cross-head guides projecting outwardly from the bonnets of the valve-cylinders and engaged by cross-heads 14; 19, an 5 arm fast on the outer end of each of the rock-shafts 15; 20, rods leading from wrist-pins in arms 19 and adapted to be connected with such valve-moving device as may be employed, be it eccentric or wrist plate or what 10 not, and 21 the bonnets secured to the outer wall of the chambers in cylinder-head 2, these bonnets serving to retain the removable valve-cylinders in place in the chambers and to close the outer ends of the valve-cylinders 15 and to support the cross-head guides 18.

The valve-cylinders are suitably bored and concentrically turned and fitted removably, but tightly, into suitably-bored seats in the inner and outer walls of the chambers in the 20 cylinder-head, the seats in the inner wall of the cylinder-head being rabbeted, as shown, and the bonnets holding the valve-cylinders in position.

Giving attention to Fig. 2, showing the 25 steam-valves, let it be noticed that both valves are line and line. Any motion of piston 8 to the left is an opening motion and any motion of piston 11 to the right is an opening motion. Hence if the arm 16 which operates these two 30 pistons has its upper end moved to the left piston 8 will open ports 7 by retreating from the engine-cylinder, while piston 11 will open by moving into the engine-cylinder, and the ports having been thus opened the closure 35 would be effected by piston 8 moving again toward the engine-cylinder while piston 11 retreats from the engine-cylinder. It is to be observed that if pistons 8 and 11 are of the same diameter they will be perfectly balanced as regards pressure in the steam-chest, 40 pressure in the engine-cylinder, and current through the ports, the valves thus moving with extreme ease. Motion is to be given to arms 16 by any properly-selected valve-moving 45 device.

In Fig. 2 it will be observed that with the valves in line-and-line position the inner ends of the pistons are substantially even with the inner surface of cylinder-head 2. Consequently the surface exposed to the steam within the engine-cylinder is practically that due to a plain cylinder-head unmodified by any valve conditions, there being no exposure of this steam to surfaces chargeable to ports or 55 passages. In calculations for the finer economies of steam as effected by heat exchanges due to surfaces exposed to the steam within the engine-cylinder it is found that the present construction provides the most favorable 60 conditions practically or theoretically obtainable, and aside from the question of exchanges of temperature as effected by the areas of metallic surfaces exposed to the steam within the cylinder it is to be noticed that 65 the volume of clearance is reduced almost to zero. The engine-piston may approach cylinder-head 2 as close as is permissible with

safety, the small clearance thus resulting being practically all that is involved in the structure, the valve system adding practically nothing to such clearance, the result being the effecting of marked economies due to the small clearance, which economies may be availed of either in steam-engines or in compressors dealing with fluids.

75 I claim as my invention—

1. The combination, substantially as set forth, of a main cylinder, a cylinder-head thereto, a pair of ported valve-cylinders disposed in said cylinder-head parallel with the main cylinder and having their inner ends opening directly into said main cylinder, a valve-piston in and entirely closing the inner end of each of said valve-cylinders, one of said valve-pistons being arranged to perform its opening office by moving toward and partially into said main cylinder, and mechanism for reciprocating said valve-pistons in the valve-cylinders.

2. The combination, substantially as set forth, of a main cylinder, a cylinder-head thereto, a pair of valve-cylinders disposed in said cylinder-head parallel with the main cylinder and having their inner ends opening directly into said main cylinder, a valve-piston in and entirely closing the inner end of each of said valve-cylinders, one of said valve-pistons being arranged to perform its opening office by moving toward and partially into said main cylinder while the other valve-piston performs its opening office by moving away from the main cylinder, and mechanism for connecting and reciprocating said valve-pistons in said valve-cylinders.

3. The combination, substantially as set forth, of a main cylinder, a cylinder-head thereto, a pair of valve-cylinders disposed in said cylinder-head parallel with the main cylinder and having their inner ends opening directly into said main cylinder, a valve-piston in each of said valve-cylinders, one of said valve-pistons being arranged to perform its opening office by moving toward and partially into said main cylinder while the other valve-piston performs its opening office by moving away from the main cylinder, a rock-shaft, arms thereon, and valve-stems from 110 said arms to said valve-pistons.

4. The combination, substantially as set forth, of a main cylinder, a cylinder-head thereto, two pairs of valve-cylinders in said cylinder-head parallel with the main cylinder and opening directly into the main cylinder, a fluid-chamber for each pair of valve-cylinders, a valve-piston in each valve-cylinder, 125 one piston of each pair performing its opening office by moving partially into the main cylinder while the other pistons open by moving in the opposite direction, and independent mechanism for moving each pair of pistons in their cylinders.

5. The combination, substantially as set forth, of a main cylinder, a cylinder-head thereto, a valve-cylinder in the cylinder-head

parallel to the main cylinder and opening directly thereinto, a bonnet closing the outer end of the valve-cylinder, a stuffing-box at the center of the bonnet, cross-head guides carried by the bonnet and projecting outwardly therefrom, a valve projecting through said stuffing-box, a cross-head on said stem and engaging said guides, and valve-moving mechanism engaging said cross-head.

6. The combination, substantially as set forth, of a main cylinder, a double-walled cylinder-head thereto, a valve-cylinder removably seated in the two walls of said cylinder-head parallel to the main cylinder and opening directly thereinto, a bonnet closing the outer end of the valve-cylinder and retaining it in its seats in said cylinder-head walls, cross-head guides carried by the bonnet, a valve-piston in the valve-cylinder, a

valve-stem therefor with a cross-head engaging said guides, and valve-moving mechanism engaging said cross-head.

7. The combination, substantially as set forth, of a main cylinder, a double-walled cylinder-head thereto formed with chambers, 25 valve-cylinders in said cylinder-head across said chambers and separately seating in the walls thereof and having their inner ends opening directly into said main cylinder, bonnets secured to the outer wall of the cylinder-head and closing said valve-cylinders, valve-pistons in the valve-cylinders, and mechanism for reciprocating the valve-pistons in their cylinders.
